UNITED STATES PATENT OFFICE.

HARRY I. PHILLIPS, OF WATERBURY, CONNECTICUT, ASSIGNEE TO SCOVILL MANUFACTURING COMPANY, OF WATERBURY, CONNECTICUT, A CORPORATION OF CONNECTICUT.

SPRING CATCH FOR VANITY BOXES.

Application filed March 27, 1923. Serial No. 627,956.

To all whom it may concern:

Be it known that I, HARRY I. PHILLIPS, a citizen of the United States, residing at Waterbury, county of New Haven and

5 State of Connecticut, have invented certain new and useful Improvements in Spring Catches for Vanity Boxes, fully described and represented in the following specification and the accompanying drawings, forming a part of the same.

This invention relates to certain improvements in boxes for carrying cosmetics, such as powder and rouge, and commonly known as vanity boxes.

10 In certain types of these vanity boxes there is provided a bottom compartment for carrying the cosmetic and a cover for covering the bottom, these parts being pivotally associated on a hinge. In order that these 15 boxes shall provide an attractive appearance which is a prime commercial requisite, the bottom is formed with an inset flange with which the cover, also provided with a flange, has telescopic engagement so that when the 20 parts are closed the cover flange and the bottom flange meet snugly and an attractive 25 appearing structure is produced.

These boxes thus formed have heretofore 30 been provided with an ordinary knob catch for holding the parts in closed position, this catch comprising a small projection on one 35 of the parts engaging with an indentation on the other. These catches have, however, been somewhat unsatisfactory in that they 40 do not positively secure the parts in closed position. It is a particular object of the 45 present invention to provide a spring catch of improved construction which shall positively hold the parts together so that they 50 can not be separated until the spring has been released, this spring catch being of 55 such construction that the parts are concealed except for the means for loosening the spring and which at the same time permits the cover and the bottom to have telescopic engagement with each other.

It is a further object of the invention to 60 produce a spring catch of simple and convenient form which may be easily assembled with the other parts of the box and which 65 shall be durable and effective in use.

With these and other objects not specifically referred to in view, the invention consists of certain novel parts, combinations 70 and arrangements which will be described

in connection with the accompanying drawings, and the novel features thereof pointed out in the claims hereunto annexed.

Referring now to these drawings—

Figure 1 is a central vertical section of 60 the box with improved catch attached, the view being partly broken away and the box being shown closed.

Figure 2 is a view similar to Fig. 1, the 65 box being shown open.

Figure 3 is a plan view looking in the direction of the arrow 3 of Fig. 2.

Figure 4 is a detail sectional view on an 70 enlarged scale, the view being taken on line 4—4 of Fig. 1.

Figure 5 is a detail sectional view on an 75 enlarged scale, the section being taken on line 5—5 of Fig. 4.

Referring now to these drawings, the box includes a bottom member 1, having up- 75 standing peripheral wall 2. This peripheral wall is inset to form a flange 3, the inset also forming an exterior shoulder 4. Pivotally associated with this bottom member 1 on a hinge 5 is a cover 6, this cover having 80 a downwardly extending peripheral wall 7. This wall 7 of the cover has a telescopic engagement with the flange 3 when the parts are in closed position, the lower edge of the 85 wall 7 seating against the shoulder 4, this construction providing a box of very neat attractive appearance.

In accordance with the present invention 90 an improved spring lock is provided for securely locking these parts together, the parts being arranged so that the locking is effected 95 between the cover and the inset flange, no part of the spring lock being visible when the box is closed except the spring release hereinafter referred to.

In the construction shown the flange 3 is 100 provided with a slot 8, and secured in the cover in any suitable manner, as by rivets 9 is a spring arm 10, this spring arm being secured at one end. The free end of this 105 arm is provided with a wing 12, this wing carrying a locking projection 13 which may be conveniently formed by indenting the wing. Extending outwardly from the free end of the arm is a release 14, this release 110 passing through a slot 15 in the flange 7 of the top, before referred to.

In the operation of the device, when the box is being locked the flange 3 passes between the projection 13 and the inner side 110

of the wall 7, the spring arm being forced inward until such time as the slot 8 arrives in line with the projection 13, whereupon the projection snaps into the slot and the parts are securely locked into position and can be freed only by the inward movement of the release 14 which frees the projections 13 from the slot in the flange.

With this construction the telescopic engagement of the parts is retained and at the same time a firm lock is effected, none of the mechanism being visible from the outside of the box when closed except the release member 14. While the invention has been shown and described in its preferred form it will be understood that certain changes and variations may be made in the specific structure disclosed without departing from the invention.

20. What I claim is.

1. In a box of the character described, the combination with a bottom having a peripheral wall, a cover having a peripheral

wall, one of these parts being inset to form a flange with which the other has telescopic engagement, a slot in the flange, a spring arm having a projection engaging the slot when the parts are closed, and a release operable from without the box for releasing the projection.

2. In a box of the character described, the combination of a bottom member having a peripheral wall inset near its top to form a flange, a cover pivotally associated with the bottom and having a peripheral wall having telescopic engagement with the flange, a slot in the flange, a spring arm secured at one end inside the cover, a wing on the free end of the arm having a projection engaging with the slot, and a release on the arm extending through an aperture in the cover wall and operable from without the box for releasing the projection.

In testimony whereof, I have hereunto set my hand.

HARRY I. PHILLIPS.
